UNITED STATES PATENT OFFICE

2,610,839

GAS-LIQUID ADMIXING APPARATUS

Charles V. De Wees, Merchantville, N. J., assignor
to U. S. Gas Generator Corp., Haddonfield,
N. J., a corporation of New Jersey

Application August 26, 1949, Serial No. 112,615

1 Claim. (Cl. 261—121)

1

This invention relates to new and useful improvements and structural refinements in gas-liquid admixing apparatus, and the principal object of the invention is to facilitate thorough and efficient admixing of a liquid into a gas, such as for example, alcohol, gasoline, benzine, etc., into air, or the like, so that the mixture derived from the apparatus is in the required, proper state of vaporization.

This object is achieved by the provision of an admixing apparatus including a tank containing a quantity of the liquid to be admixed, a submerged aerating unit in the liquid in the tank, and a buoyant spraying unit floating on the liquid, matters being so arranged that air or some other gas is delivered to the aerating unit under pressure and is caused to bubble upwardly through the liquid in the tank, while at the same time, liquid from the tank is delivered under pressure to the spraying unit and is discharged thereby into the gas expelled by the aerator, so that a thorough, efficient and complete admixing of the gas and liquid occurs.

An important feature of the invention resides in the provision of means for condensing any improperly vaporized liquid such as may leave the tank after the admixing operation, and returning the condensation to the liquid in the tank for subsequent use.

An additional feature of the invention lies in its simplicity of construction, ease and convenience of operation and in its adaptability to economical manufacture.

With the above more important objects and features in view and such other objects and features as may become apparent as the specification proceeds, the invention consists essentially in the arrangement and construction of parts as illustrated in the accompanying drawings, in which:

Figure 1 is a vertical cross sectional view of the invention,

Figure 2 is a cross sectional view, taken substantially in the plane of the line 2—2 in Figure 1, and

Figure 3 is a cross sectional view, taken substantially in the plane of the line 3—3 in Figure 1.

Like characters of reference are employed to designate like parts in the specification and throughout the several views.

Referring now to the accompanying drawings in detail, the invention consists of a gas-liquid admixing apparatus designated generally by the reference character 10, the same embodying in its construction an upright, substantially cylindrical tank 12 which is intended to receive in the lower portion thereof a quantity of liquid to be admixed, the normal level of which is indicated at 14.

The upper end wall 16 of the tank 12 carries an electric motor 18, the armature of which is coupled to a suitable liquid pump 20 and also,

through the medium of a suitable gear box 22, to an air or gas compressor 24.

The intake duct 26 of this compressor is equipped with a suitable filter 28 whereby the duct communicates with the atmosphere, while the outlet of the compressor communicates with a further duct 30. This duct extends through the top wall 16 downwardly into the tank 12, and the lower end thereof carries and is in communication with a disk-like, substantially circular housing of an aerating unit 32.

It is to be noted that this aerating unit is submerged with respect to the liquid level 14 and that the circumferential wall of the aerator housing is formed with a plurality of outlet openings 34. Moreover, a set of mutually divergent baffle strips 36 are provided within the aerator housing 32, these strips defining therebetween a plurality of air passages 38, each of which extends from the lower end of the duct 30 to one of the outlet openings 34, as is best shown in Figure 3. It is to be noted that in order to facilitate this structural arrangement, the duct 30 is eccentrically disposed with respect to the aerator housing 32, as will be readily understood.

A spraying unit 40 floats upon the liquid in the housing 12, the unit 40 including in its construction a buoyant, disk-like member 42 on which is mounted a circular chamber 44. This chamber, in turn, is provided with a plurality of upwardly directed spraying nozzles 46, and it is to be noted that the chamber 44 is also equipped with an upright feed tube 48. The nozzles 46 are disposed above the level of the liquid in the tank, and flotation of the unit 40 on the liquid safeguards against any possibility of the nozzles being submerged if the level of liquid should rise.

A foraminous baffle plate 50 is mounted in the tank 12 above the spraying unit 40, and the tube 48 extends slidably through a suitable aperture formed in the plate 50 and is slidably telescoped on the lower end portion of a tubular conduit 52. This conduit is connected to the outlet 54 of the aforementioned liquid pump 20, and it is to be noted that suitable packing 56 is provided in the upper end portion of the tube 48, in order to assure that all liquid delivered through the conduit 52 is conveyed, without leakage, through the tube 48 to the chamber 44.

A filtering screen 58 is provided in the tank 12 above the foraminous baffle 50, the conduit 52 passing downwardly through the screen 58, while the aforementioned duct 30 passes downwardly through the screen 58 as well as through the baffle 50, as will be clearly apparent.

The intake 60 of the pump 20 is connected to a feed tube 62, the latter extending downwardly through the screen 58 and through the baffle 50 and carrying at its lower end a filter element 64 which is submerged in the liquid in the tank 12, substantially as shown.

It may be added at this point that the level of

liquid in the tank 12 may be observed by means of a water glass 66 of conventional design, with which the tank is provided, and the lower end portion of the tank is also equipped with a drain valve 68 in order that the liquid from the tank may be drained for purposes of cleaning the tank at periodic intervals.

The upper end portion of the duct 30 is provided with a plurality of lateral outlets 10 which communicate with the interior of the tank 12 above the liquid level 14, the purpose of these outlets being hereinafter more fully described.

It should be also noted that the upper end portion of the tank is equipped with a mixture outlet 12 which, in turn, communicates with a vapor condenser unit 74. This unit simply assumes the form of a suitable housing containing a plurality of staggered baffles 16, and the condenser 74, in turn, communicates through the medium of a duct 78 with a pressure regulator 80 of conventional design, from which, in turn, the gaseous mixture is delivered by means of a conduit 82 to a point where it is to be consumed.

For cleaning purposes, the condenser unit 74 is equipped with a drain plug 84, and it will be also noted that the condenser unit is connected by means of a drain tube 90 to the lower end portion of the tank 12.

Finally, a gas pressure actuated electric switch 92 of any suitable type is mounted on the condenser unit 74 and is operatively connected by means of a cable 94 to the motor 18 and also, by a further cable 96 to a source of electric current.

Having thus described the construction of the invention, its method of operation will now be explained.

Assuming that the switch 92 is closed and the motor 18 is in operation, the compressor 24 will draw air from the atmosphere through the filter 28 and will force that air through the duct 30 into the aerating unit 34, from which, in turn, the air will be discharged through the opening 34 and will be caused to bubble upwardly through the liquid in the tank 12.

After passing upwardly through the liquid in the tank, the air will ascend to the upper portion of the tank as indicated by the arrows 98, while at the same time the pump 20 will draw the liquid from the bottom portion of the tank through the pipe 62 and will deliver that liquid, under pressure, through the tubes 52, 48 to the spraying unit 40.

This liquid will be discharged, under pressure, through the nozzles 46 and will impact against the under surface of the foraminous baffle plate 50, and being deflected thereby, will fall downwardly, as indicated by the arrows 100.

This, of course, will result in a thorough admixing of the liquid and air, inasmuch as they are passing in relatively opposite directions (as evidenced by the arrows 98, 100), and the mixture will pass upwardly through the baffle plate 50 and through the screen 58 to the vapor condenser 74 and thence through the pressure regulator 80 to its point of consumption.

The screen 58 will effectively prevent any heavy particles of foreign matter from gaining access to the condenser unit 74, while the latter unit itself, will prevent improperly vaporized liquid from passing through the pressure regulator 80. Such improperly vaporized liquid will be returned through the drain tube 90 to the bottom portion of the tank 12, as will be clearly apparent.

It is to be noted that the pump 20 operates simultaneously with the compressor 24, and the

switch 92 will periodically interrupt the operation of the motor 18 as well as of the pump 20 and the compressor 24, when the pressure of the mixture in the condenser unit 74 reaches a predetermined limit. On the other hand, the lateral outlet 10 and the duct 30, having openings of predetermined size, will assure that the mixture of liquid and gas is of predetermined proportions.

By virtue of the floating action of the spraying unit 40 on the liquid, the nozzles 46 will be closely spaced from the baffle plate 50 when the liquid level is high, and the liquid will be sprayed from the nozzles with considerable velocity and impact the baffle plate to propagate the mixing action. On the other hand, with the liquid at low level, the greater distance of the nozzles from the baffle plate will retard the admixing action accordingly.

It is believed that the advantages and use of the invention will be clearly apparent from the foregoing disclosure, and accordingly, further description thereof at this point is deemed unnecessary.

Having described the invention, what is claimed as new is:

A gas-liquid admixing apparatus comprising an upright tank adapted to contain a quantity of liquid in the lower portion thereof, an aerating unit submerged in the liquid in said tank, a gas compressor, a duct connecting said compressor to said aerating unit, a buoyant spraying unit floating on the liquid in said tank and including a chamber and a plurality of upwardly directed nozzles thereon, said nozzles being disposed above the level of liquid in the tank, a liquid pump having an inlet and an outlet, a tubular conduit connected to the outlet of said pump and extending downwardly in the upper portion of said tank, an upright feed tube provided on said chamber and slidably telescoped on said conduit whereby said spraying unit may rise and fall with the level of liquid in the tank, a suction pipe extending from the lower end portion of said tank to the inlet of said pump, a foraminous baffle plate provided in said tank above said spraying unit whereby to be impacted by liquid discharged upwardly from said nozzles, means for simultaneously driving said compressor and said pump, a mixture outlet in the upper end portion of said tank, and a vapor condenser provided on said outlet, said aerating unit comprising a substantially circular housing provided with an eccentrically disposed inlet opening in communication with said duct, the circumferential wall of said housing being formed with a plurality of outlet openings, and a plurality of mutually divergent baffle strips provided in said housing, said strips defining therebetween a set of passages each extending from said inlet opening to one of said outlet openings.

CHARLES V. DE WEES.
